(57) **CLAIM**

The ornamental design for a skid having a skid frame configured to accommodate multiple material delivery bins, as shown and described.

DESCRIPTION

FIG. 1 is a front perspective view for a skid having a skid frame configured to accommodate multiple material delivery bins;

FIG. 2 is a rear perspective view of the design for the skid of FIG. 1;

FIG. 3 is a front view of the design for the skid of FIG. 1; FIG. 4 is a right side view of the design for the skid of FIG. 1;

FIG. 5 is a left side view of the design for the skid of FIG. 1;

FIG. 6 is a top view of the design for the skid of FIG. 1; FIG. 7 is a bottom view of the design for the skid of FIG. 1; and,

FIG. 8 is a rear view of the design for the skid of FIG. 1. In these drawings, the solid lines illustrate the claimed ornamental design, whereas the broken lines illustrate environmental features that form no part of the claimed ornamental design.

1 Claim, 7 Drawing Sheets
